UNITED STATES PATENT OFFICE.

FRANK J. TONE, OF NIAGARA FALLS, NEW YORK, ASSIGNOR TO THE CARBORUNDUM COMPANY, OF NIAGARA FALLS, NEW YORK, A CORPORATION OF PENNSYLVANIA.

GRINDING WHEEL AND HOLDER THEREFOR.

Application filed June 23, 1925. Serial No. 39,104.

For grinding certain classes of work, such as the inside surfaces of bath tubs to prepare them for enameling, and similar castings, for example, the grinding wheel is mounted 5 on the end of a flexible operating shaft, in order to enable the operator to move the wheel from point to point, and both the face and the edge of the grinding wheel are used as grinding surfaces. This work is very 10 hard on the grinding wheel and causes it to wear away rapidly, necessitating frequent replacement of wheels. Heretofore such wheels have been formed cup-shaped and the operating shaft extended through the 15 bottom of the cup and the wheel secured thereto by means of a nut engaging the threaded end of the shaft inside the hollow cup. With this method of mounting it was impossible to wear down the wheel lower 20 than the nut, so that the stub to be thrown away constituted a considerable portion of the wheel. Also, there was considerable 25 danger to the operator by reason of the liability of the rapidly rotating wheel cracking and then flying to pieces, as this method of mounting did not afford any support for the cracked wheel tending to prevent it from flying to pieces.

By the present invention I have provided 30 an improved form of grinding wheel and mounting therefor designed to overcome the above objectionable features inherent in the old method of mounting grinding wheels of this character.

35 The invention is illustrated in the accompanying drawings, wherein:

Figure 1 is a side elevation of one form of grinding wheel and holder mounted on the end of a flexible operating shaft and embodying my invention;

Figure 2 is a sectional view of the grinding wheel and holder;

Figure 3 is an inverted plan view, partly broken away, of the grinding wheel;

Figure 4 is a plan view of the holder;

Figure 5 is sectional view of another form of grinding wheel and holder embodying my invention;

Figure 6 is an inverted plan view, partly broken away, of the grinding wheel shown in Figure 5;

Figure 7 is a plan view of the holder; and

Figure 8 is a detail sectional view of the holder.

55 Referring to the embodiment of the in-

vention shown in Figures 1 to 4, inclusive, the grinding wheel 2 has a central bore 3 and a reduced hub portion 4 projecting from one end face thereof. The hub portion 4 has a plurality of uniformly spaced lugs 5 60 projecting radially from its outer periphery, these lugs having undercut curved outer surfaces 6 which are eccentric with respect to the axis of the wheel, thereby providing 65 cam surfaces.

The holder comprises a plate 7 having a central hole to receive the screw-threaded end 8 of the operating shaft 9, the plate being adapted to be clamped between an enlarged portion 10 of the shaft and a nut 11 70 mounted on the screw-threaded end 8. The plate 10 has a plurality of integral lugs 12 projecting upwardly therefrom at the peripheral edge of the plate and corresponding in number to the number of lugs 5 on the hub of the grinding wheel. The lugs 12 have undercut inner curved edges which are eccentric to the axis of the plate 7 and are adapted to engage the undercut curved surfaces 6 of the lugs 5. 75

In applying the holder to the wheel, the lugs 12 are inserted through the spaces between the lugs 5 of the grinding wheel and then the wheel and the holder are relatively rotated to cause the eccentric undercut inner surfaces of the lugs 12 to frictionally engage the undercut outer surfaces of the lugs 5. Mounted in openings in the plates 7 are set screws 13 which are adapted to be set up 80 against the end face of the hub portion 4, whereby to create sufficient friction between the lugs 5 and the lugs 12 and between the set screws and the end face of the hub portion 4 to hold the wheel against turning in its holder. 85

In the form of the invention illustrated in Figures 5 to 8, inclusive, the hub portion 4^a of the wheel 2^a is provided with spaced lugs 5^a having undercut curved outer surfaces 6^a which are concentric with the axis 100 of the wheel.

The plate 7^a in this form of the invention has lugs 12^a, the inner undercut edges of which are concentric with axis of the plate. Adjacent one end of each lug is a pin 14, 105 these pins being provided to limit relative rotation between the wheel and plate when the lugs 12^a are slipped through the spaces between the lugs 5^a and the wheel and plate relatively rotated to bring the lugs 5^a and 110

12^a into cooperative relation. When the holder has been applied to the wheel in this manner, the set screws 13^a are set up to hold the wheel against relative rotation in the holder.

It will be noted that in both forms of the invention the holder engages the reduced hub portion only of the wheel, thereby permitting the wheel to be worn down almost, 10 if not quite, to said hub portion, which constitutes only a relatively small portion of the wheel. Moreover, the hub is at least partially surrounded by the holder, so that the holder will tend to hold the wheel together in case it cracks in service and thereby lessen the danger of the wheel exploding. 15 Moreover, I make no claim broadly to these features, as they constitute the invention of Hobart C. Beach and are claimed in his 20 copending application Serial No. 39,011 filed of even date herewith.

I claim:

1. A grinding wheel assembly including an abrasive wheel formed of bonded abrasive grains having an integral hub portion of reduced diameter thereon, a series of lugs disposed around the periphery of the hub portion, the peripheral surface of each lug being undercut, each lug also being outwardly curved from one end toward the other, and a metal holder secured to the 25

hub portion having a central portion with a series of undercut lugs on the face thereof corresponding to the lugs on the said hub portion of the wheel, said lugs on the holder 35 being adapted to embrace and interfit with the lugs of the said hub portion and to be forced into wedging relation therewith.

2. A grinding wheel assembly including an abrasive wheel formed of bonded abrasive grains having an integral hub portion of reduced diameter thereon, a series of lugs disposed around the periphery of the hub portion, the peripheral surface of each lug being undercut, each lug also being outwardly curved from one end toward the other, and a metal holder secured to the hub portion having a central portion with a series of undercut lugs on the face thereof corresponding to the lugs on the said hub 40 portion of the wheel, said lugs on the holder 45 being adapted to embrace and interfit with the lugs of the said hub portion and to be forced into wedging relation therewith, and adjustable means on the holder for pressing 50 against the end of said reduced hub portion of the wheel to increase the frictional engagement between the said cooperating lugs.

In testimony whereof I have hereunto set my hand.

FRANK J. TONE.
